135,000

DESIGN FOR A MILK DISPENSER

Lannie F. Norris, Minneapolis, Minn.

Application June 17, 1942, Serial No. 107,225

Term of patent 7 years

To all whom it may concern:

Be it known that I, Lannie F. Norris, a citizen of the United States, residing at Minneapolis, in the county of Hennepin and State of Minnesota, have invented a new, original, and ornamental Design for Milk Dispensers, of which the following is a specification, reference being had to the accompanying drawing, forming a part thereof, and in which

4—4 of Figure 1.

I claim:

The ornamental design for a milk dispenser, substantially as shown.

LANNIE F. NORRIS.
